UNITED STATES PATENT OFFICE

2,648,745

CIRCUIT INTERRUPTER

Winthrop M. Leeds, Pittsburgh, Pa., assignor to
Westinghouse Electric Corporation, East Pitts-
burgh, Pa., a corporation of Pennsylvania

Application May 18, 1950, Serial No. 162,656

14 Claims. (Cl. 200—150)

1

The invention relates to circuit interrupters in general, and, more particularly, to arc extinguishing structures therefor.

A general object of my invention is to provide an improved circuit interrupter particularly adapted for the lower voltage ranges in which a single pressure-generating break and a single interrupting break are adequate for interruption of the circuit through the pole of the interrupter.

It has been the general practice when applying circuit interrupters of the self-generated fluid flow type, involving a pressure-generating break and an interrupting break, to circuit interrupters of the steel tank type in which terminal bushings extend interiorly within the tank, to provide duplicate units which are generally disposed at the lower ends of the two terminal bushings. One object of my invention is to adapt a self-generating type of fluid flow circuit interrupter to an interrupter of the tank type involving only a single pressure-generating break and a single interrupting break for interrupting the current passing through each pole of the interrupter.

With a pressure-generating break on one terminal of the interrupter and an interrupting break on the other terminal of the interrupter, some means for transmitting the pressure driven fluid, such as oil, from one break to the other is required. Previous solutions to this problem, are set forth in U. S. patent applications filed May 18, 1950, Serial No. 162,655, and filed May 18, 1950, Serial No. 162,657 by me and assigned to the assignee of the instant application, the latter application maturing into U. S. Patent 2,627,566 issued February 3, 1953. The structure set forth in the aforesaid applications utilized a horizontally-disposed cylindrical tube or a horizontal interrupting structure of insulating material for bridging the two terminal bushings of the interrupter. However, horizontal insulating surfaces are known to collect carbon which may in some instances encourage flash-over during arc rupture when high recovery voltage transients are applied to the ends of these horizontal surfaces. When this occurs, it will mean that arcing will take place externally of the extinguishing structure and not internally thereof. The possibility exists that under such conditions arcing might take place between the lower ends of the two terminal bushings, and the resulting pressure during such continued arcing in the liquid would rupture the tank before series breakers closer to the generator would be relayed to function.

It is an object of the present invention to improve the structure by utilizing a conducting pressure transmitting conduit and also employing arc extinguishing units extending an appreciable vertical distance along the direction of the line of separation of the contacts.

Another object is to provide an improved cir-

2

cuit interrupter of the foregoing type in which improved arc extinguishing units are associated with the pressure-generating break and with the interrupting break.

5 Still a further object is to provide such an interrupter of the foregoing type in which the arc extinguishing units are substantially enclosed at the ends thereof adjacent the terminal bushings.

Further objects and advantages will readily be 10 come apparent upon reading the following specification taken in conjunction with the drawings in which:

Fig. 1 is a side elevational view, partially in vertical section, of a circuit interrupter embodying my invention and shown in the fully open circuit position;

Fig. 2 is an enlarged vertical sectional view through the improved arc extinguishing structure of Fig. 1, the contacts being shown in the closed circuit position;

Fig. 3 is a view similar to that of Fig. 2 but showing the contact structure in the partially open circuit position;

Fig. 4 is a vertical sectional view taken along the line IV—IV of Fig. 2;

Fig. 5 is a vertical sectional view taken along the line V—V of Fig. 2;

Fig. 6 is an enlarged bottom plan view of the arc extinguishing structure of Fig. 1;

Fig. 7 is a sectional view taken along the line VII—VII of Fig. 5;

Fig. 8 is a sectional view taken along the line VIII—VIII of Fig. 4;

Fig. 9 is a sectional view taken along the line IX—IX of Fig. 4;

Fig. 10 is a vertical sectional view through a modified type of circuit interrupter embodying the principles of my invention and shown in the closed circuit position;

Fig. 11 is a view similar to that of Fig. 10 showing the contact structure in the partially open circuit position;

Fig. 12 is a bottom plan view of the arc extinguishing structures of Figs. 10 and 11;

Fig. 13 is a vertical sectional view through a modified type of circuit interrupter similar in over-all principle to that of Fig. 2 but having the upper ends of the arc extinguishing units substantially enclosed to increase the generation of the pressure within the arc extinguishing units; and

Fig. 14 is a sectional view through a tank type three pole circuit interrupter illustrating the arrangement of the three poles to minimize external flash-over.

Referring to the drawings, and more particularly to Fig. 1 thereof, the reference numeral 1 designates a suitable enclosure such as a tank filled to the level 2 with a suitable arc extinguishing fluid 3, in this instance circuit breaker oil.

Depending from the cover 4 of the tank 1, are two terminal bushings 5, 6 at the lower ends of which are disposed stationary contact assemblies 7, 8.

Movable within the tank 1 and bridging the contact assemblies 7, 8 is a movable arc extinguishing assemblage generally designated by the reference numeral 9. The assemblage 9 includes a pressure-generating arc extinguishing unit 10 and a movable interrupting arc extinguishing unit generally designated by the reference character 11.

The two units 10, 11 are rigidly secured together and are movable simultaneously by means of conducting conduit means, generally designated by the reference numeral 12 and including two conducting tubes 13, 14, as more clearly shown in Fig. 6.

A rod-shaped pressure-generating contact 15 and a rod-shaped interrupting contact 16 are rigidly secured to the extremities of a conducting cross-bar 17, the latter being reciprocally movable in a vertical direction by an insulating lift rod 18. Preferably the cross-bar 17 includes a pair of cross-straps 19 of metallic material. As more clearly shown in Fig. 2, the lift rod 18 has an enlarged portion 20, which is arranged to strike a shoulder 21 forming an integral part of the conduit means 12. An accelerating compression spring 22 is disposed between the shoulder portion 21 and the cross-bar 17 as shown more clearly in Fig. 2.

The movable arc extinguishing assemblage 9 will now be described. The movable pressure-generating arc extinguishing unit 10 includes an insulating cylinder 24, in which is internally disposed two types of insulating plates. One type is designated by the reference character 26 and is shown more clearly in Fig. 7. The insulating plate 26 has a cutout portion 27 of the configuration shown. The other type of insulating plate is designated by the reference character 28 and is similar in exterior configuration to that of the plate 26. However, the plate 28 is provided with a small aperture 29 forming an orifice through which the rod-shaped pressure-generating contact 15 is withdrawn. The orifice insulating plate 28 is also provided with two cutout portions 30, the purpose for which will appear more fully hereinafter. The insulating plates are alternately disposed within the cylinder 24, the lower end of which is threadedly secured at 30 to an upstanding portion 31 of the casting forming the conduit means 12.

The top-most insulating orifice plate 28 is beveled, as at 32, to accommodate the lower end of the contact assemblage 7. As illustrated in Fig. 2, the stationary contact assemblage 7 includes a cylindrical housing 33 preferably of conducting material having a tapered lower end 34. Interiorly disposed within the housing 33 are a plurality of contact segments 35 biased radially inwardly by compression springs 36 to make good contacting engagement with the upper end of the contact rod 15. Flexible conductors 37 may be employed to electrically connect the contact segments 35 with the conducting clamp 38, the latter being threadedly secured to the lower end of the terminal stud 39, and clamped thereto by the nut 40 and bolt 41.

Positioned at the other end of the conduit means 12 is the interrupting arc extinguishing unit 11, which will now be described. An insulating cylinder 43 has its lower end threadedly secured, as at 44, to the casting forming the con-

duit means 12. Interiorly positioned within the cylinder 43 are a plurality of insulating plates disposed in contiguous relation. The top-most insulating plate is designated by the reference character 46 and merely has an aperture or orifice 47 provided therethrough. The upper side of the aperture 47 is beveled, as at 32, to accommodate the tapered lowered end of the housing 48 of the stationary contact assemblage 8. The internal construction of the stationary contact assemblage 8 is the same as that of the contact assemblage 7, heretofore described, and hence will not need to be further described.

Immediately below the insulating orifice plate 46 is an insulating composite vent plate generally designated by the reference character 49 and including two horizontally spaced segmental insulating plates 50, as shown more clearly in Fig. 8. Each segmental insulating plate 50 has a cutout portion 25, and the spacing between the two insulating plates 50 provides a pair of diametrically opposed exhaust passages 51. Apertures 52 are provided in the cylinder 43 to permit unimpeded flow of fluid, in this instance oil or gaseous products of oil decomposition when heated by an arc, out of the interrupting unit 11 during the interruption process.

Immediately below the vent plate 49 is a second orifice plate 46 similar in construction to the top plate 46 except that no bevel 32 is provided. Immediately below the second orifice plate 46 is an insulating inlet plate 54, the configuration of which is more clearly shown in Fig. 9. The inlet plate 54 has a cutout portion 55 to permit the oil passing through the conduit means 12 to pass substantially radially inwardly toward the interrupting arc established between the rod contact 16 and the stationary contact 8, and designated by the reference character 56 in Fig. 3.

Below the inlet plate 54 is an orifice plate 57 which is similar in construction to the orifice plates 46 previously described except that two cutout portions 58 are provided, the purpose of which will appear more clearly hereinafter. Below the orifice plate 57 is a second vent plate 49 having a construction as previously described. Below the vent plate is a second orifice plate 57, which is followed by a second inlet plate 54. Below the inlet plate 54 is another orifice plate 57.

The operation of my improved circuit interrupter will now be described. In the closed circuit position of the interrupter, as shown in Fig. 2, the electrical circuit therethrough includes terminal stud 39, stationary contact assemblage 7, rod-shaped pressure-generating contact 15, conducting crossbar 17, rod-shaped interrupting contact 16, stationary contact assemblage 8 to terminal stud 59.

When it is desired to open the electrical circuit passing through the interrupter, suitable mechanism, not shown, but which is responsive to either manual operation or to the existence of over-load conditions existing in the electrical circuit controlled by the interrupter, functions to cause downward opening movement of the insulating lift rod 18. This downward movement of the lift rod 18 is accelerated by the biasing action exerted by the accelerating compression spring 22, which functions initially to hold the conducting conduit means 12 and the units 10, 11 upwardly against the stationary contact assemblage 7, 8. Consequently, the pressure-generating arc 60 (Fig. 3) is established rapidly between the contacts 7, 15, and the interrupting arc 56

(Fig. 3) is established between the contacts 16, 8 within the respective units 10, 11 while the latter remain temporarily positioned against the lower ends of the contact assemblage 7, 8.

The establishment of the pressure-generating arc 60 within the pressure-generating arc passage 61, defined by the several insulating plates disposed within the cylinder 24, generates pressure by decomposing the adjacently disposed oil, resulting in a flow of oil outwardly, as shown by the arrows 62 of Fig. 7, within the vent plates 26 and downwardly through the vertical flow channels 63 formed by the alignment of the several cutout portions 25. The oil thus passes downwardly within the unit 10 in a manner more clearly shown by the arrows in Fig. 5. The lower ends of the vertical flow channels 63 communicate with the two conducting tubes 13, 14 to permit the passage of oil toward the right, as viewed in Fig. 3, and into the vented right-hand grid 11.

As shown in Fig. 4, the oil passes upwardly from the conducting tubes 13, 14 to strike the interrupting arc 56 through the two insulating inlet plates 54. Each insulating inlet plate 54 provides a pair of inlet passages 65 to permit communication between the oil moving upwardly in the vertical flow channels 66 and the interrupting arc passage 64. The oil passes substantially radially inwardly toward the interrupting arc 56 through the several pairs of inlet passages 65, and is forced to pass through the apertures or orifices 47 provided by the several orifice plates 57. Contaminated oil flows out of the exhaust passages 51 provided by the composite vent plates 49, as shown by the arrows in Fig. 8.

Interruption of the interrupting arc 56 soon follows with a consequent breaking of the electrical circuit passing through the breaker. As the tension relaxes in the accelerating spring 22, the weight of the movable arc extinguishing assemblage 9 causes an initial downward movement of the assemblage 9, made more positive a moment later by engagement of the enlarged portion 20 of the lift rod 18 with the shoulder portion 21 of the assemblage 9. Thus the entire movable assemblage 9 is lowered to the full open circuit position of the interrupter shown in Fig. 1.

It will be observed that during the closing stroke the cross-bar 17 will move up initially before any appreciable movement of the heavier assemblage 9 takes place. This will cause the contacts 15, 16 to raise relative to the assemblage 9 so that the upper tips of the contacts 15, 16 approach the top of the units 10, 11 to engage the stationary contacts 7, 8 at substantially the same time as engagement of the units 10, 11 with the contact assemblage 7, 8. Thus, any flash-over occurring during the closing stroke with voltage across the terminals of the interrupter will occur in substantially clean oil adjacent the tops of the units 10, 11, and not interiorly thereof.

From the foregoing description of this embodiment of my invention, it will be apparent that I have provided an improved circuit interrupter of the high speed type, particularly adaptable for the lower voltage ranges, that is, 69 kv. and below, in which a single pressure-generating break and a single interrupting break are adequate for effecting clearing of the circuit. The construction is obviously simple and not susceptible to contamination of the arcing passages during the closing stroke. The conducting conduit means 12 results in the upstanding portion 75

of the units 10, 11 holding the voltage, there being no horizontal surfaces to collect deposits of carbon, and thereby to give rise to hazards of flashover occurring during arc rupture when high recovery voltage transients are applied to the interrupter. It will be observed that in the fully open circuit position of the interrupter, as shown in Fig. 1, two isolated disconnect gaps are provided in clean oil to hold the voltage.

Referring to the construction set forth in Figs. 10-12 it will be observed that in this simpler embodiment of my invention, for applications where the highest speeds of arc interruption are not required, the conducting conduit means 12 is rigidly secured to the lift rod 18. In other words, I employ a clamp 69 securing the lower end of the lift rod 18 to the two conducting tubes 13, 14 as shown by the bottom plan view of Fig. 12. The pressure-generating unit 70 has an internal construction identical to that of the unit 10 of Fig. 2, as far as configuration of the insulating plates are concerned. However, in this instance a stationary rod contact 71 is secured to the clamp 72, the latter being affixed to the lower end of the terminal stud 39. Cooperable with the lower tip of the stationary contact 71 is a movable contact 73 biased upwardly by a compression spring 74. Flexible conductors 75 are employed to carry the current from the contact 73 to the casting 76 forming the conducting conduit means 12.

The movable interrupting arc extinguishing unit 77 is identical in configuration to that of the movable arc extinguishing unit 11 of Fig. 2 with the exception that the contact structure is modified to incorporate a stationary interrupting contact 78 and a movable interrupting contact 79. Again, the contact 79 is biased upwardly by a compression spring 74, and flexible conductors 75 are employed to permit passage of the current from the movable interrupting contact 79 to the casting 76. Interruption of the circuit follows in a manner previously described, it being noted that here there is a positive interconnection between the lift rod 18 and the movable arc extinguishing assemblage 80.

In the construction shown in Figs. 10 through 12 it will be observed that due to the greater inertia of the moving parts, butt contacts 71, 73 and 78, 79 are employed to keep the over-all operating time as short as possible. This arrangement, as shown in Figs. 10-12, has the chief advantage of simplicity.

Fig. 13 shows a modified form of interrupter in which the tops of the units 83, 84 are enclosed to bring about the existence of higher pressure conditions within said units in spite of a small downward movement of the units before the arc is extinguished. As set forth, a movable disconnect contact 85 forming an integral portion of a contact cap 86 is cooperable in the closed position with a stationary disconnect contact 87, the latter being clamped to the lower end of the terminal stud 39. A valve 88 is employed including apertures 89 provided in the contact cap 86 and a ring shaped valve plate 90. The latter, in the closed position of the device, rests upon the contact segments 91 thereby permitting opening of the apertures 89 and the passage of oil therethrough.

During the opening operation the movable disconnect contact 85 separates from the stationary disconnect contact 87 only following arc extinction.

Associated with the interrupting unit 84 is a movable disconnect contact 92 cooperable with a

stationary disconnect contact 83. The cap structure 94 serves to permit high pressure to be attained within the interrupting unit 84, and the valve structure 95 functions the same as the valve 88 heretofore described.

During the opening operation the interrupting action takes place in the same manner as described in connection with Fig. 2, higher pressure conditions being attained because of the enclosed structure. Following arc extinction, the movable disconnect contacts 85, 92 are withdrawn from the stationary disconnect contacts 87, 93 to insert a pair of isolating gaps in the circuit.

Fig. 14 shows a three pole circuit interrupter with the three poles 97, 98 and 99 enclosed within in a single enclosure or tank 96. Each of the poles 97—99 is of the type heretofore described in connection with Figs. 1—9. It will be observed that the assemblages are alternated so that venting from the interrupting units 11 takes place in such manner as to minimize external flash-over. That is, there is no possibility for commingling of the exhaust gases to contaminate the surrounding oil, to the extent of causing flash-over to occur between units during the opening operation. By the construction provided, the possibility of external flash-over is reduced to a minimum, and this results in a very compact arrangement, as shown, in which the three poles 97, 98 and 99 may be disposed within a single enclosure or tank 96.

From the foregoing description of several embodiments of my invention, it will be clearly understood that I have provided an improved form of interrupter particularly adapted for the lower voltage ranges. It will be noted that for such ranges where a single pressure-generating break and a single interrupting break are adequate for each pole of the interrupter, I have not placed both breaks on a single side of the pole, but have placed one break at one side and the other break at the other side of the pole. Mechanical advantages are thereby obtained. By the use of conducting fluid bridging conduits the construction furthermore minimizes the presence of horizontal surfaces of insulation which might collect carbon deposits, and thereby results in efficient arc extinction with little possibility of flash-over.

Although I have shown and described specific structures, it is to be clearly understood that the same were merely for the purpose of illustration, and that changes and modifications may readily be made therein by those skilled in the art without departing from the spirit and scope of the appended claims.

I claim as my invention:

1. In a circuit interrupter of the liquid break type, a tank containing an arc extinguishing liquid, two terminal bushings extending into the tank, relatively stationary contact means disposed at the interior end of each terminal bushing, a movable arc extinguishing assemblage including a pressure-generating unit and an interrupting unit hydraulically interconnected by a conducting conduit means, movable contact means including a movable pressure-generating contact and a movable interrupting contact, a movable conducting cross-bar electrically and mechanically connecting the two movable contacts, an operating rod fixed to the cross-bar to cause the actuation of the same, and a lost-motion connection between the movable contact means and the movable arc extinguishing assemblage so that during the initial portion of the opening operation only the movable contact

means first moves and subsequently, after an appreciable delay, the arc-extinguishing assemblage moves therewith.

2. In a circuit interrupter of the liquid break type, a tank containing an arc extinguishing liquid, two terminal bushings extending into the tank, relatively stationary contact means disposed at the interior end of each terminal bushing, a movable arc extinguishing assemblage including a pressure-generating unit and an interrupting unit hydraulically interconnected by a conducting conduit means, movable contact means including a movable pressure-generating contact and a movable interrupting contact, a conducting cross-bar electrically and mechanically connecting the two movable contacts, an operating rod fixed to the cross-bar to cause the actuation of the same, a lost-motion connection between the movable contact means and the movable arc extinguishing assemblage, means biasing the movable arc extinguishing assemblage to the closed circuit position, and the operating rod having an actuating portion to forceably drive the extinguishing assemblage therewith during the final portion of the opening operation.

3. In a circuit interrupter of the liquid break type, a tank containing an arc extinguishing liquid, two terminal bushings extending into the tank, relatively stationary contact means disposed at the interior end of each terminal bushing, a movable arc extinguishing assemblage including a pressure-generating unit and an interrupting unit hydraulically interconnected by a conducting conduit means, movable contact means including a movable pressure-generating contact and a movable interrupting contact, a conducting cross-bar electrically and mechanically connecting the two movable contacts, an operating rod fixed to the cross-bar to cause the actuation of the same, a lost-motion connection between the movable contact means and the movable arc extinguishing assemblage so that during the initial portion of the opening operation only the movable contact means first moves and subsequently, after an appreciable delay, the arc-extinguishing assemblage moves therewith, and the movable contacts being movable through the units to engage the stationary contact means in the closed circuit position of the interrupter.

4. In a circuit interrupter of the liquid break type, a tank containing an arc extinguishing liquid, two terminal bushings extending into the tank, relatively stationary contact means disposed at the interior end of each terminal bushing, a movable arc extinguishing assemblage including a pressure-generating unit and an interrupting unit hydraulically interconnected by a conducting conduit means, both the pressure-generating and interrupting units being formed in part of insulating material extending upwardly vertically from the ends of the conducting conduit means, movable contact means movable with the assemblage and including a movable pressure-generating contact and a movable interrupting contact, and an operating rod fixed to the conducting conduit means to cause the actuation of the same.

5. In a circuit interrupter of the liquid break type, a tank containing an arc extinguishing liquid, two terminal bushings extending into the tank, relatively stationary contact means disposed at the interior end of each terminal bushing, a movable arc extinguishing assem-

blage including a pressure-generating unit and an interrupting unit hydraulically interconnected by a conducting conduit means, movable contact means having a lost motion connection with the assemblage including a movable pressure-generating contact and a movable interrupting contact, an insulating operating rod for actuating the assemblage and the movable contact means, and the assemblage remaining momentarily stationary during the initial portion of the opening operation while the movable contacts move relative thereto establishing arcing within the pressure-generating and interrupting units.

6. In a circuit interrupter of the liquid break type, a tank containing an arc extinguishing liquid, two terminal bushings extending into the tank, relatively stationary contact means disposed at the interior end of each terminal bushing, a movable arc extinguishing assemblage including a pressure-generating unit and an interrupting unit hydraulically interconnected by a conducting conduit means, movable contact means including a movable pressure-generating contact and a movable interrupting contact, a conducting cross-bar electrically and mechanically connecting the two movable contacts, an operating rod fixed to the cross-bar to cause the actuation of the same, and a lost-motion connection between the movable contact means and the movable arc extinguishing assemblage, movable disconnect means associated with the end of each unit and contacting the stationary contact means in the closed circuit position, and the movable contacts pulling away from the movable disconnect means interiorly of the units during the opening operation.

7. In a circuit interrupter of the liquid break type, a tank containing an arc extinguishing liquid, two terminal bushings extending into the tank, relatively stationary contact means disposed at the interior end of each terminal bushing, a movable arc extinguishing assemblage including a pressure-generating unit and an interrupting unit hydraulically interconnected by a conducting conduit means, movable contact means including a movable pressure-generating contact and a movable interrupting contact, a conducting cross-bar electrically and mechanically connecting the two movable contacts, an operating rod fixed to the cross-bar to cause the actuation of the same, a lost-motion connection between the movable contact means and the movable arc extinguishing assemblage, movable disconnect means associated with the end of each unit and contacting the stationary contact means in the closed circuit position, the movable contacts pulling away from the movable disconnect means interiorly of the units during the opening operation, and the movable disconnect means enclosing said ends of the units to increase the pressure formed therein during the opening operation.

8. In a circuit interrupter of the liquid break type, a tank containing an arc extinguishing liquid, two terminal bushings extending into the tank, relatively stationary contact means disposed at the interior end of each terminal bushing, a movable arc extinguishing assemblage including a pressure-generating unit and an interrupting unit hydraulically interconnected by a conducting conduit means, movable contact means including a movable pressure-generating contact and a movable interrupting contact, a conducting cross-bar electrically and mechanical-

ly connecting the two movable contacts, an operating rod fixed to the cross-bar to cause the actuation of the same, a lost-motion connection between the movable contact means and the movable arc extinguishing assemblage, movable disconnect means associated with the end of each unit and contacting the stationary contact means in the closed circuit position, the movable contacts pulling away from the movable disconnect means interiorly of the units during the opening operation, the movable disconnect means enclosing said ends of the units to increase the pressure formed therein during the opening operation, and valve means associated with the movable disconnect means to vent the units at the end of the opening operation.

9. In a circuit interrupter of the liquid break type, a tank containing an arc extinguishing liquid, two terminal bushings extending into the tank, relatively stationary contact means disposed at the interior end of each terminal bushing, a movable arc extinguishing assemblage including a pressure-generating unit and an interrupting unit hydraulically interconnected by a conducting conduit means, movable contact means including a movable pressure-generating contact and a movable interrupting contact, a conducting cross-bar electrically and mechanically connecting the two movable contacts, an operating rod fixed to the cross-bar to cause the actuation of the same, a lost-motion connection between the movable contact means and the movable arc extinguishing assemblage, and the conducting conduit means comprising two metallic tubes between which the cross-bar operates.

10. A liquid break circuit interrupter including a pair of spaced rod-shaped stationary contacts, a movable pressure-generating insulating arc extinguishing unit, a movable interrupting insulating arc extinguishing unit, hollow conducting conduit means electrically and hydraulically interconnecting the two units, both the pressure-generating and interrupting units extending upwardly from the ends of the conducting conduit means, an operating rod fixed to the conduit means intermediate the ends thereof to cause the actuation of the same, each unit having a passage formed therein open at one end into which the rod-shaped stationary contacts enter during the final portion of the closing stroke, a pair of movable contacts disposed at the other end of the passages and engaging the stationary contacts in the closed circuit position, and the stationary contacts being completely removed from the units in the fully open circuit position of the interrupter.

11. In a circuit interrupter of the liquid break type, a tank containing an arc-extinguishing liquid, two terminal bushings extending into the tank, relatively stationary contact means disposed at the interior end of each terminal bushing, a movable arc-extinguishing assemblage including a pressure-generating unit and an interrupting unit hydraulically interconnected by a conducting conduit means, both the pressure-generating and interrupting units being in part composed of insulating material and extending an appreciable distance vertically upwardly at the two ends of the conducting conduit means, movable contact means including a movable pressure-generating contact and a movable interrupting contact, a movable conducting crossbar electrically and mechanically connecting the two movable contacts, an operating rod fixed to the crossbar to cause the actuation of the same, and

11

a lost-motion connection between the movable contact means and the movable arc-extinguishing assemblage.

12. In a circuit interrupter of the liquid break type, a tank containing an arc-extinguishing liquid, two terminal bushings extending into the tank, relatively stationary contact means disposed at the interior end of each terminal bushing, a movable arc-extinguishing assemblage including a pressure-generating unit and an interrupting unit hydraulically interconnected by a conducting conduit means, both the pressure-generating and interrupting units extending vertically upwardly an appreciable distance at the two ends of the conducting conduit means and being composed at least in part of insulating material, and movable contact means electrically interconnecting the pressure-generating and interrupting units.

13. In a circuit interrupter of the liquid break type, a tank containing an arc-extinguishing liquid, two terminal bushings extending into the tank, relatively stationary contact means disposed at the interior end of each terminal bushing, a movable arc-extinguishing assemblage including a pressure-generating unit and an interrupting unit hydraulically interconnected by a conducting conduit means, both the pressure-generating and interrupting units being at least in part composed of insulating material and extending vertically upwardly an appreciable distance at the outer ends of the conducting conduit means, movable contact means including a movable pressure-generating contact and a movable interrupting contact, a conducting cross-bar electrically and mechanically connecting the two movable contacts, an operating rod fixed to the cross-bar to cause the actuation of the same, a lost-motion connection between the movable contact means and the movable arc-extinguishing assemblage, means biasing the movable arc-extinguishing assemblage to the closed circuit position of the interrupter.

12

sition, and the operating rod having an actuating portion to forceably drive the extinguishing assemblage therewith during the final portion of the opening operation.

5 14. In a circuit interrupter of the liquid break type, a tank containing an arc-extinguishing liquid, two terminal bushings extending into the tank, relatively stationary contact means disposed at the interior end of each terminal bushing, a movable arc-extinguishing assemblage including a pressure-generating unit and an interrupting unit hydraulically interconnected by a conducting conduit means, both the pressure-generating and interrupting units being at least 10 in part composed of insulating material and extending vertically upwardly an appreciable distance at the outer two ends of the conducting conduit means, movable contact means including a movable pressure-generating contact and a movable interrupting contact, a conducting cross-bar electrically and mechanically connecting the two movable contacts, an operating rod fixed to the cross-bar to cause the actuation of the same, a lost-motion connection between the movable contact means and the movable arc-extinguishing assemblage, and the movable contacts movable through the units to engage the stationary contact means in the closed circuit position of the interrupter.
